UNITED STATES PATENT OFFICE.

CARRIE GIBBS, OF SOUTHSEA, ENGLAND.

CYCLING-SKIRT.

SPECIFICATION forming part of Letters Patent No. 630,498, dated August 8, 1899.

Application filed May 23, 1899. Serial No. 717,901. (No model.)

To all whom it may concern:

Be it known that I, CARRIE GIBBS, a resident of "Tresillian," Marmion road, Southsea, in the county of Hants, England, have invented new and useful Improvements in Cycling-Skirts, of which the following is a full, clear, and exact description.

This invention relates to an improvement in cycling-skirts, and has for its object to prevent the flowing drapery toward the rear of the side portions of the skirt from being swung about ungracefully by the action of the knees on the fore part of the skirt when pedaling or from being blown about by a high wind, this object being accomplished by the provision of means whereby the plaits or folds of the skirt are retained in such position that they always depend gracefully at either side of the dress-guard of the back wheel, notwithstanding the movements of the rider's legs or the action of the wind.

Reference is to be had to the accompanying drawings, forming part of this specification, wherein—

Figure 1 represents a rear view of the skirt as it appears when the wearer is cycling, the skirt being partly broken away in order to illustrate more clearly the interior portions of the skirt to which the invention more particularly relates and by means of which the plaits of the skirt are retained in position when cycling. Fig. 2 is a development in the flat of the various portions of the skirt, showing their relation to each other. Fig. 3 represents a horizontal section of the skirt as worn, taken at a point below the level of the knees of the wearer, the skirt being represented as somewhat distended or spread out laterally to show the plaits and the means by which they are retained in position.

The same letters of reference denote like parts in all the figures.

The pieces of which the skirt is formed comprise a front width A, a back width B, a pair of front gores C C, and a pair of back gores D D, all cut out of the forms shown in Fig. 2 and stitched together as follows: The front width A is seamed at *a a* to the front gores C, which are seamed at *c* to the back gores D, which are seamed at *d d* to the back width B. The latter is cut out of the form shown—that is to say, it has formed in one with it lateral

extensions or wings E of substantially the form shown in Fig. 2, which when the skirt is made up are stitched by their anterior edges *e* to the inside of the front width A along lines *e' e'* symmetrically at either side of the center, so that the said wings E will extend from back to front within the skirt, as shown in Fig. 3. These wings E are of just sufficient length to retain the plaits of the skirt in proper position when the lower members of the rider's legs are passed between them and the skirt itself, as shown in Fig. 1 and indicated by dotted lines in Fig. 3. The plaits at the back of the skirt are formed by the back gores D being outwardly folded along the lines *ff* and by inward or reverse folds being formed at the seams *d d* and by the back width B having outward folds or creases *g g* and a central *h h*, which extends from the hem to a short distance below the waistband, and is completed by two inward folds at *h' h'*, which extend down a short distance only from the waistband. The plaits of the material thus formed by these reverse folds are shown spread out somewhat in Fig. 3, and they are of graduated depth, as is well understood, the effect being to cause the rear part of the skirt to depend gracefully, as shown in Fig. 1.

In order to prevent the plaits formed by the folds *f* and the adjacent side portions of the skirt from being blown out by the wind or caused to swing about excessively by the action of the knees on the front part of the skirt in pedaling, a plurality of narrow tie-straps F, of elastic webbing or strips of material, are stitched by their opposite ends to the two edges of each gore D at the seams *d* and *c*, these tie-straps F forming, in effect, laterally-extending continuations of the wings E from the point of origin of the latter at the seams *d* to the seams *c*, and they have for effect to limit the lateral spreading of the plaits formed by the gores D. These straps F are graduated in length according to the varying depth of the plait which they are intended to retain, the straps being longer toward the bottom of the skirt and gradually diminishing in length as they proceed upward. They are at short distances apart, so that should the wind get under the skirt the plaits of the skirt will be effectually prevented from being blown out and distended, balloon-like, as would other-

wise happen, so that by this means the graceful draping of the skirt is under all circumstances preserved.

I claim—

- 5 As a new article of manufacture, a cycling-skirt having the rear portion thereof plaited as herein described and having extensions or wings cut out in one piece with the back width, and seamed to the front width of the skirt, so as to pass between the wearer's legs and connect the back plaits to the front of the skirt, and a plurality of cross-straps form-

ing cross connections within the plaits formed by the folds of the back gores, to the opposite sides of which the said cross-straps are attached so as to limit the lateral spreading of said plaits substantially as specified. 15

Signed by the said CARRIE GIBBS this 1st day of May, 1899.

CARRIE GIBBS.

In presence of—

W. J. MAIN,
M. WHETTEM.
